BOBBIN CHUTE FOR LOOMS

Richard G. Turner, Worcester, Mass., assignor
to Crompton & Knowles Loom Works, Worcester, Mass., a corporation of Massachusetts

Application October 12, 1946, Serial No. 703,073

6 Claims. (Cl. 139—255)

1

This invention relates to improvements in bobbin chutes for weft replenishing looms and it is the general object of the invention to provide a chute so constructed as to cause the butt of an expelled bobbin to move forwardly at a greater rate than that of the bobbin tip.

Bobbin changing looms are ordinarily provided with transfer mechanism to expel a depleted bobbin from the shuttle and direct it downwardly along a bobbin chute toward a bobbin receiver or can. It is important to prevent damage to the tip of the bobbin, since the weft unwinds over it during the weaving operation. The butt of the bobbin is much stronger than the tip and has no contact with the weft. As bobbin chutes have been constructed heretofore however they have directed the expelled bobbins forwardly in such a manner that the tip could strike the front wall of the bobbin can before the butt end and be damaged.

It is an important object of my present invention to provide a bobbin chute having a forwardly concave surface for the bobbin butt and another surface for the bobbin tip, and wherein the surfaces are so related that at the instant the bobbin leaves the bobbin chute its butt is moving in a direction having a forward component greater than the forward component of the tip.

It is another object of the invention to provide a bobbin chute having a concave surface on a butt deflector and to which is secured a bobbin tip guide having a straight tip engaging surface which at its upper and lower ends coincides with the concave surface but is forward of the concave surface intermediate its ends.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a forward part of the loom having my improved bobbin chute applied thereto.

Fig. 2 is an enlarged view looking in the direction of diagonal arrow 2, Fig. 1.

Fig. 3 is a vertical section on line 3—3 of Fig. 2, and

Fig. 4 is a view looking in the direction of arrow 4, Fig. 1.

Referring particularly to Fig. 1, the loom frame 10 supports a reserve bobbin magazine part of which is indicated at M. Reserve bobbins are transferred one at a time from the magazine into a shuttle S when the latter is in the shuttle

2

box 11 carried by the lay 12 of the loom. Transferrer arm 13 is part of the magazine and during replenishing operation descends to insert a full bobbin indicated at 14 into the shuttle and at the same time expels the depleted bobbin 15 from the shuttle. Incident to the transferring operation the depleted bobbin is discharged downwardly and is guided by a chute designated generally at C toward a bobbin receiver or can 16 which may be of any approved form. Bobbin chutes may either be carried by the lay or have stationary supports, but in the present instance the bobbin chute C is shown as attached to the lay since this is the more usual construction in weft replenishing looms. The bobbin can 16 will have a front wall 17 against which the bobbins are directed and from which they fall toward the bottom of the can.

The matter thus far described is of usual construction except the chute C as will be pointed out hereinafter.

The chute comprises a rigid plate 20 which may be made of cast iron and secured to the lay under the shuttle box 11 and swing back and forth with the shuttle box as the lay reciprocates. Secured to plate 20 is a bobbin butt deflector 21 which may be made of sheet metal and be attached to plate 20 as at 22. The deflector need not necessarily be made of sheet metal, but has a surface 23 which is concave as viewed from the front of the loom so that it curves downwardly and forwardly from an upper part thereof to the bottom. The left side of deflector 21 extends along a forwardly projecting bobbin butt guiding flange 24 formed as part of chute 20, see Fig. 2.

As shown in Figs. 2 and 3 a bobbin tip guide 25 is secured to the deflector 21 by screws or the like 26. The reason for this construction is to permit the deflector and guide to be made as a complete unit and then attached to the plate 20, although the particular means by which the bobbin tip guide derives its support from the plate 20 is immaterial.

The tip guide 25 has a tapered upper end 30 and a similar tapered lower end 31, while the intermediate part thereof designated at 32 is relatively thick so that the surface 33 of the guide which engages the bobbin barrel either at or near its tip will be forward of the concave surface of the deflector at points intermediate the tapered ends of the guide 25. As shown more particularly in Fig. 3, the lower end of the guide 25 terminates at the bottom of deflector 21, but this relationship is a matter of choice, and the guide 25 can if desired project beyond the bottom

of the deflector, but it is not desirable that it terminate very far above the lower end of the deflector. The upper part of surface 33 terminates either at or close to the upper end of the concave surface 23 so that the bobbin in its descent will glide onto the surface 33 without an abrupt movement of the bobbin tip.

In operation, the expelled bobbin will descend with its butt B and tip T moving down along the upper part of the plate 20. The butt then engages the concave surface of the deflector 21 and moves downwardly along the latter in a path behind the surface 33 along which the tip end of the bobbin moves. As the butt approaches the bottom of the deflector the lower end of surface 23 causes the bobbin butt to be delivered from the bottom of the deflector in a forward and downward direction designated by arrow b, Fig. 3. Simultaneously, that part of the bobbin either at or adjacent to its tip T leaves the bottom of surface 33 moving in the direction of arrow t, Fig. 3. The arrows b and t are respectively tangential to surface 23 and a continuation of surface 33.

Assuming that both butt and tip of the bobbin are moving at the same rate the butt will tend to lead or be in advance of the tip and strike the front wall 17 of the can 16 before the tip end strikes the wall 17. The tip thereafter strikes the wall 17 with a much reduced force and for this reason is subject to much less damage than has been the case in bobbin chutes as heretofore constructed.

The bobbin chute set forth herein can be used with any type of bobbin receiver, such as the usual galvanized sheet iron can, but it has particular advantage when used with a type of multi-compartment bobbin receiver set forth in my copending application Serial No. 703,074 filed on even date herewith, now Patent No. 2,428,251. In that application the chute is claimed in combination with the particular form of bobbin receiver set forth therein. Since the advantages of the bobbin chute are not restricted to use with a cloth or multi-compartmented bobbin receiver, the bobbin chute itself is claimed in this present application.

From the foregoing it will be seen that I have provided a simple form of bobbin chute so constructed that at the instant a bobbin leaves it the butt is moving in a direction having a greater forward component than that of the bobbin tip, and the result of this difference in rates of movement causes the butt of the bobbin to strike the bobbin can first and thereby reduce the force with which the bobbin tip strikes wall 17 later. It will be seen that this result is accomplished by providing the bobbin butt deflector with surface 23 which is concave as viewed from the front of the loom and providing the bobbin tip or barrel guide 25 with a surface 33 which extends for the greater part of its extent along a path forward of surface 23. The two surfaces 23 and 33 in effect produce a twisting of the descending bobbin resulting in forward movement of the bobbin butt relatively to the tip. The surface 33 need not necessarily be straight as shown, but it is desirable that its intermediate parts between the ends 30 and 31 be forward of the corresponding parts of the surface 23. It is also desirable that the lower end 31 of the guide 25 terminate approximately at the bottom of the concave surface 23 so that the bobbin butt and tip may leave the chute at approximately the same time and at the instant when they are moving forwardly at different rates.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a shuttle box from which a bobbin is discharged during a replenishing operation toward a bobbin receiver, a bobbin chute under the lay having a concave bobbin butt engaging surface and having a second surface for engagement with the bobbin between the butt and tip thereof, both of said surfaces extending downwardly and forwardly and the first surface being so related to the second surface as to cause the butt of the bobbin when the latter leaves the chute to travel forwardly at a rate greater than the rate at which the tip of the bobbin moves forwardly.
2. In a weft replenishing loom having a shuttle box from which a bobbin is discharged during a replenishing operation toward a bobbin receiver, a bobbin chute under the shuttle box having two laterally spaced surfaces one of which is concave with respect to the front of the loom and positioned to engage the butt of the bobbin and the other of which is substantially straight and inclined downwardly and forwardly and positioned to engage part of the bobbin adjacent to the tip end thereof, said two surfaces effective when the bobbin leaves the chute to cause the butt end of the bobbin to move forwardly at a rate greater than the rate at which the tip end of the bobbin moves forwardly.
3. In a weft replenishing loom having a shuttle box from which a bobbin is discharged during a replenishing operation toward a bobbin receiver, a bobbin chute under the shuttle box having a surface to engage the bobbin butt and having a second surface to engage the bobbin between the butt and tip thereof, said surfaces being so constructed and related to each other that as a bobbin descends along the chute the butt end thereof moves forwardly in a curved path concave from the front of the loom, while the tip moves downwardly and forwardly along a substantially straight path.
4. In a weft replenishing loom having a shuttle box from which a bobbin is discharged during a replenishing operation toward a bobbin receiver, a bobbin chute under the shuttle box having a deflector formed with a bobbin butt engaging surface concave with respect to the front of the loom, a bobbin barrel engaging guide having a barrel engaging surface which extends downwardly and forwardly, the upper and lower ends of said surface being substantially coincident with said concave surface and the intermediate part of the barrel engaging surface being forward of that part of the concave surface between the top and bottom of the guide, said surfaces effective to cause the butt of the bobbin to move forwardly at a given rate and the tip of the bobbin to move forwardly at a lesser rate when the bobbin leaves the chute.
5. In a weft replenishing loom having a shuttle box from which a bobbin is discharged during a replenishing operation toward a bobbin receiver, a bobbin chute under the shuttle box having two surfaces directed downwardly and forwardly, one surface being concave and for the butt of the bobbin and the other surface being substantially straight and for the barrel of the bobbin, said surfaces effective to engage their respective parts of the bobbin as the latter is discharged and

descends along the chute and causing the butt of the bobbin to move forwardly relatively to the tip of the bobbin as the descending bobbin approaches the bottom of the chute.

6. In a weft replenishing loom having a shuttle box from which a bobbin is discharged during a replenishing operation toward a bobbin receiver, a bobbin chute under the shuttle box having two surfaces directed downwardly and forwardly, one surface for the butt of the bobbin and the other surface for the barrel of the bobbin, said surfaces effective to engage their respective parts of the bobbin as the latter is discharged and descends along the chute and twisting the bobbin in such manner as to cause the butt and tip to move

15

forwardly at different rates the greater of which is that of the butt as the bobbin leaves the chute.
